UNITED STATES PATENT OFFICE.

DAN WILKINSON, OF PERU, INDIANA.

MULTIPLE-CYLINDER STEAM-ENGINE.

SPECIFICATION forming part of Letters Patent No. 376,459, dated January 17, 1888.

Application filed August 23, 1887. Serial No. 247,652. (No model.)

To all whom it may concern:

Be it known that I, DAN WILKINSON, a citizen of the United States of America, residing at Peru, in the county of Miami and State of Indiana, have invented certain new and useful Improvements in Multiple-Cylinder Steam-Engines, of which the following is a specification, reference being had therein to the accompanying drawings.

10 My invention relates to steam-engines of the class termed "multiple-cylinder;" and it has for its object to provide an engine of this class whose crank-shaft, by reason of the peculiar construction and arrangement of itself and connected parts, shall be perfectly balanced at all points in its revolution, thus avoiding friction and admitting of a high rate of speed.

15 The invention will first be described in connection with the accompanying drawings, and then pointed out in the claims.

Figure 1 of the drawings is a perspective view of a two-cylinder steam-engine illustrating my invention. Fig. 2 is a plan view of 20 the same with the pistons at full stroke.

25 Referring to the drawings, A represents the bed-plate resting on standards *a* and supporting the cylinders, guides, cross-heads, connecting-rods, crank, fly-wheel, eccentrics, and valve-stems. Midway of the bed-plate there is a transverse opening or depression, *a'*, to allow of the rotation of the crank-shaft.

30 B B' are the steam-cylinders, placed opposite each other on the bed-plate, as shown, and secured thereto in any suitable manner, and C C' are the steam-chests, D D' the steam-supply pipes, and E E' the exhaust-pipes.

35 F represents the piston-rods; G, the cross-heads; H, the guides for the cross-heads, and 40 I I' the connecting-rods, one of which, I, is forked, as shown, and both of which are pivoted to the cross-heads in direct alignment with the piston-rods.

45 J represents the crank-shaft, journaled in pillow-blocks *j* on the bed-plate midway between the cylinders. This shaft is constructed with four arms, 1 2 3 4, joined together by integrally-formed round portions, (not seen,) on which the forward ends of the connecting-50 rods are journaled, the forked rod I being journaled between arms 1 and 2 and 3 and 4, and

the straight rod I' between arms 2 and 3, as clearly shown in Fig. 2, it being understood that the fork of rod I is of sufficient length and width to allow arms 2 and 3 to pass through it in the revolution of the shaft. The arms are of proper weight to balance the shaft with the fly-wheel and eccentrics attached.

55 K is the fly-wheel.

The cylinders are exact duplicates, as are also the valves, ports, and piston-rods, and the connecting-rods and eccentrics are of equal weight, uniformly distributed along their entire length. Now, with the fly-wheel accurately balanced the crank-shaft will be equally balanced at any and all points in its revolution, and as the connecting-rods exert their power in direct lines with the piston-rods excessive friction and all lateral strains on the moving parts are avoided, and as a consequence a high rate of speed is attainable with safety to the engine.

60 I am aware that a two cylinder engine whose cylinders are each the counterpart of the other mounted opposite each other on a continuous bed-plate, and whose connecting-rods operate on a common crank-shaft located midway between the cylinders, is not new; but, so far as I am aware, while the pistons connect centrally with the cross heads, the connecting-rods are set to one side of this center, and also connect correspondingly with the crank-shaft. Such construction results in a continuous transverse strain on the stuffing-boxes of the cylinders, the connections of the pistons and the connecting-rods at the cross-heads, and on the 65 boxings supporting the crank-shaft; and it also results, when a high speed is attempted, in undue friction and heating, which can be obviated only by running at ordinary speed.

70 Having thus described my invention, what I claim as new, and desire to secure by Letters Patent, is—

75 1. In a multiple-cylinder engine, the combination, with a continuous bed-plate, of two cylinders of equal size set opposite each other on said plate, two pistons, two guides, two cross-heads to which the pistons are centrally attached, a crank-shaft having three points of attachment for the connecting-rods and located 80 in bearings on the said bed-plate midway between the cylinders, and two connecting-rods,

one of which is forked and the other straight, attached at their rear ends to the cross-heads in alignment with the pistons and at their forward ends to the crank-shaft, all constructed 5 in the manner described.

2. In an engine of the class described mounted on a continuous bed-plate, the crank-shaft mounted midway between the cylinders and having four arms, in combination with the 10 fly-wheel, the eccentrics, and the forked and

straight connecting-rods attached to the cross-heads and to the crank-shaft, in the manner shown and described.

In testimony whereof I affix my signature in presence of two witnesses.

DAN WILKINSON.
